UNITED STATES PATENT OFFICE.

WILLIAM L. BJUR, OF NEW YORK, N. Y.

DESIGN FOR A PIANO-CASE.

45,520.

Specification for Design. Patented Mar. 31, 1914.

Application filed January 12, 1914. Serial No. 811,764. Term of patent 7 years.

To all whom it may concern:

Be it known that I, WILLIAM L. BJUR, a citizen of the United States, and a resident of the borough of Manhattan, city, county, and State of New York, have invented a new, original, and ornamental Design for a Piano-Case, of which the following is a specification, reference being had to the accompanying drawing, forming part thereof.

The figure is a perspective view of a piano-case, showing my new design.

I claim:

The ornamental design for a piano-case, as shown,

WILLIAM L. BJUR,

Witnesses:

GEORGE DUELY,
GEORGE F. USBELK,
